(57) CLAIM

The ornamental design for a wand, as shown and described.

DESCRIPTION

FIG. 1 is a front perspective view of a wand showing our new design;

FIG. 2 is a right side view thereof;

FIG. 3 is a left side view thereof;

FIG. 4 is a rear view thereof;

FIG. 5 is a front view thereof;

FIG. 6 is a top view thereof;

FIG. 7 is a bottom view thereof;

FIG. 8 is a rear perspective view thereof;

FIG. 9 is a front perspective view of the wand of FIGS. 1-8 shown without surface shading and disclaimed regions;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a rear perspective view thereof.

The broken line showing of the indicia on the handle and butt end of the wand in FIGS. 1-8 forms no part of the claimed design.
